[57] **CLAIM**

The ornamental design for a stud for modular building system, as shown and described.

DESCRIPTION

FIG. 1 is a perspective view of a stud for modular building system constructed in accordance with our new design; FIG. 2 is an end view of the stud for modular building system;

FIG. 3 is a top plan view of the stud for modular building system;

FIG. 4 is a bottom plan view of the stud for modular building system; and,

FIG. 5 is a side elevation view of the stud for modular building system.

The stud for modular building system is broken in the center to disclose indefinite length.
